UNITED STATES PATENT OFFICE.

FREDERICK PEITER, OF CLEVELAND, OHIO, ASSIGNOR TO THE GAS MACHINERY COMPANY, OF CLEVELAND, OHIO, A CORPORATION OF OHIO.

GAS AND AIR MIXER.

1,160,196.

Specification of Letters Patent. Patented Nov. 16, 1915.

Application filed April 23, 1913. Serial No. 763,154.

To all whom it may concern:

Be it known that I, FREDERICK PEITER, a citizen of the United States, resident of Cleveland, county of Cuyahoga, and State of Ohio, have invented a new and useful Improvement in Gas and Air Mixers, of which the following is a specification, the principle of the invention being herein explained and the best mode in which I have 10 contemplated applying that principle, so as to distinguish it from other inventions.

My invention relates to gas and air mixers for gas-burning apparatus, its object being to provide such a mixer which will 15 be efficient in its use and which will be capable of adjustment for the purpose of regulating combustion within the chamber.

A further object is to provide a gas and air mixer particularly adapted for use in 20 apparatus in which the fuel-gas is discharged downwardly into the chamber from above.

The said invention consists of means hereinafter fully described and particularly set 25 forth in the claims.

The annexed drawings and the following description set forth in detail certain means embodying my invention, the disclosed means, however, constituting but one of 30 various mechanical forms in which the principle of the invention may be applied.

In said annexed drawings:—Figure 1 is an axial section of a gas-burning apparatus which includes in its structure combustion-chambers having vertical axes. Fig. 2 is a section taken upon the plane indicated by line II—II in Fig. 1. Fig. 3 is a section taken upon the plane indicated by line III—III in Fig. 1. Fig. 4 is a section taken upon 40 the plane indicated by line IV—IV in Fig. 1. Fig. 5 is a section similar to that shown in Fig. 1 and illustrating a modified form of my invention. Fig. 6 is a section taken upon the plane indicated by line VI—VI in 45 Fig. 5.

In the illustrated form of the device embodying my invention I have shown a construction including a pair of vertical combustion-chambers 1, 1, between which is located an air-duct 2. The upper end of each of these chambers is provided with a circular opening 3 through which extends downwardly a fuel-nozzle 4. This opening 50 communicates with a vertical fuel-duct 5. In the form of device shown in Figs. 1 and

2, the nozzle 4 consists of two separate and disconnected parts 6 and 7, the part 6 consisting of a cylindrical structure made of suitable refractory material and formed with a vertical cylindrical main duct 8. 63 Below the opening 3 and upon opposite sides of the chamber is formed the corbeling 9, 9, and the lower end of the part 6 of the nozzle rests loosely upon this corbeling. The upper portion of this part extends some distance 65 into the duct 5 and that portion of the latter adjacent thereto is formed with an inwardly projecting annular shoulder 10. This shoulder is located slightly above the upper end of the nozzle-part 6 and upon it rests the 70 flange portion 7 of the nozzle which is formed with the central cylindrical opening 11 co-axial with the duct 8.

The lower extremity of the nozzle is intersected by a transverse duct 12 communicating with the main nozzle duct 8 as shown in 75 Figs. 1 and 2, and the width of this transverse duct is substantially equal to the diameter of the duct 8. As shown this diameter is somewhat less than the distance between 80 the upper portions of the corbeling as shown in Fig. 1.

Discharging in horizontal planes above the lower extremity of each nozzle and upon opposite sides of a plane passing through the nozzles' axes and also passing through the air-duct 2, are two auxiliary transverse air-ducts 13, 13. The inlet ends of each of these ducts communicates with the air-duct 2 as shown in Fig. 1, so that it will be seen 85 that four such auxiliary transverse air-ducts communicate with the latter, one pair discharging into each of the combustion-chambers 1, Fig. 3.

In order that the nozzles may be readily 95 removed and replaced from above, the diameters of the two portions 6 and 7 are made somewhat less than the diameters of the adjacent parts of duct 5.

In the operation of the above described 100 apparatus, the fuel-gas passes downwardly through the ducts 5, through the nozzles 4 and is discharged from the lower end of the latter. The flange portion 7 of each nozzle prevents the leakage of the gas through the annular space between the nozzle-portions 4 and the adjacent parts of the ducts 5. In addition to discharging downwardly 105 from the end of the nozzles, the gas also passes laterally through the two branches 110

of the transverse duct 12 where it meets the incoming air from the air-ducts 13, 13, as shown by the arrows in Fig. 2. The upper end of the air-duct 2 is of course closed by suitable means (not shown). When it is desired to change the location of the zone in which the mixture of gas and air takes place, the depth of the transverse ducts 12 may be altered by chipping out the refractory material for that purpose, whereby regulation of combustion may be obtained, as will be readily understood by those skilled in the art. In this manner it will be seen therefore, that the location of the lower extremity of the main duct 8 of each nozzle, may be altered without changing the length or point of support of the lower portion of the nozzle.

In the modified form of nozzle shown in Figs. 5 and 6 the flange portion 7 is made integral with the lower portion 6, the corbeling 9 being dispensed with. As in the first-described structure, the said flange portion 7 rests upon the annular shoulder 10. When it is desired to change the location of the mixing zone in this form of the nozzle, the latter is withdrawn and the lower end chipped off, thereby shortening the nozzle and changing the location of the discharging end thereof.

In the first form of nozzle described, as before noted the shoulder 10 is located slightly above the upper end of the nozzle part 6. This feature is adopted for the purpose of preventing the flange-portion 7 from coming into contact with the upper end of the nozzle portion 6, thereby permitting this

flange portion always to rest snugly in contact with the shoulder 10 and thus prevent leakage.

Having fully described my invention, what I claim and desire to secure by Letters Patent is:—

1. In a fuel-duct construction for gas-burning apparatus, the combination with a combustion-chamber; a gas duct communicating with the top of said chamber; a fuel-nozzle extending into said chamber and supported in said duct; an air-supply duct; and two branch ducts communicating with said air-supply duct and communicating with the interior of said combustion-chamber upon opposite sides of a plane passing through the axis of said nozzle.

2. In a fuel-duct construction for gas-burning apparatus, the combination with a combustion-chamber; a gas duct communicating with the top of said chamber; a fuel-nozzle supported in said duct and extending into said chamber; an air-supply duct; and two branch ducts communicating with said air-supply duct and communicating with said chamber upon opposite sides of a plane passing through the axis of said nozzle and in planes perpendicular to said axis and located above the lower extremity of said nozzle.

Signed by me, this 10th day of April, 1913.

F. PEITER.
